UNITED STATES PATENT OFFICE.

ROBERT McMILLEN, OF PITTSBURGH, PENNSYLVANIA.

QUICK-ACTING WRENCH.

1,163,428.

Specification of Letters Patent.

Patented Dec. 7, 1915.

Application filed April 8, 1914. Serial No. 830,378.

To all whom it may concern:

Be it known that I, ROBERT McMILLEN, a citizen of the United States, residing at Pittsburgh, in the county of Allegheny and State of Pennsylvania, have invented new and useful Improvements in Quick-Acting Wrenches, of which the following is a specification.

The object of this invention is to provide a novel form of wrench which shall be quick-acting in its nature, and operable, with a maximum of celerity and ease, to actuate the movable jaw toward and away from the fixed jaw.

15 A further object is to provide a device of this nature which shall be composed of a minimum number of parts, and which will thus be exceedingly simple in construction; whereby the wrench may be manufactured 20 and marketed at an attractive figure, so as to complete with the wrenches now on the market.

With these objects in view, and others some of which may appear as the specification proceeds and the nature of the invention more fully appears, the invention comprehends the novel construction, combination and arrangement of parts, as will be herein-after fully described in the specification, 30 summed up in the claims, and illustrated in the drawing.

In the drawing, in which like reference-characters denote corresponding parts throughout the several views: Figure 1 is a 35 side elevation of a wrench embodying my improvements; Fig. 2 is a top plan view thereof; Fig. 3 is a longitudinal section; and Fig. 4 is a detail sectional view on the line 4—4, Fig. 1.

40 Referring, now, in detail, to the drawing: 3 designates a fixed jaw carried at one end of a shank 2, the other end whereof is provided with a handle 12. The shank 2 is provided, longitudinally, along a portion of its top, 45 with ratchet-teeth, forming a rack 9.

4 designates a complementary, movable jaw carried at one end of a shank 4^a, the other end whereof is provided with a handle 4^b inclined from, or at an angle to, the handle 12.

50 Desirably, the jaw 4, shank 4^a and handle 4^b are formed in two complementary halves or sections, the shank portions 4^a of which embrace the shank 2; and said two sections or halves are suitably united, as by rivets 13.

55 The shank 4^a is provided with a longitudi-

nally-extending slot 4^c, through which the shank 2 projects.

Seated in an interior, substantially annular socket 11, toward the top of the shank 4^a, and capable of a partial rotary movement 60 therein, is the substantially annular terminal 5^a of a pawl or dog 5, provided with complementary ratchet-teeth engageable with the teeth of the rack 9. Upward movement of the dog or pawl 5 is limited by an inclined 65 ledge or shoulder 11^a carried by the top portion of the shank 4^a. Means are provided for normally maintaining the dog or pawl 5 in engagement with the rack 9, and, in this instance, these means comprehend a leaf 70 spring 6, one end of which is secured, as at 7, to the under surface of the handle 4^b, and the other end whereof projects into the slot 4^c and is seated in a notch 5^b in one end of the pawl or dog 5. Means are provided, also, 75 for moving the dog 5 out of engagement with the rack 9, against the tension or stress of the spring 6; and, in this instance, said means comprehend a lever 8, having fulcrum-trunnions 10, 10, seated in the opposite 80 walls of the slot 4^c. One end of the lever 8 projects into a notch 12 in the end of the dog 5, and above the notch 5^b, and the other end of said lever is preferably provided with a finger-piece 8^a for convenient manipulation 85 of the lever.

2^a is a shoulder at the point of union of the shank 2 and the handle 12, which, in the operation of the wrench, engages with a nose 4^d carried at the top of the shank 4^a, whereby 90 movement of either the shank 4^a or the shank 2, in one direction, is limited.

Obviously, in the operation of the wrench, when it is desired to move the jaw 4 toward the jaw 3, the operator presses downward 95 upon the finger-piece 8^a, rocking the lever 8 on its fulcrum, and lifting the dog 5 out of engagement with the rack 9, whereupon the jaw 4 may be shifted quickly toward the jaw 3, until the two jaws 3 and 4 clamp the object to be operated upon, such as a pipe or nut; the operator then removing his finger from the lever 8 and the dog 5 once more automatically engaging the rack 9, under the influence of the spring 6.

Elaborating upon the above description of the operation, it may be said that, assuming the jaws are in closed position, when the wrench is taken up by the operator to do some work, the operator holds the wrench in 110

a vertical position, then presses downward upon the lever 8, releasing the dog 5 from engagement with the rack 9, whereupon the shank 2 drops, by gravity, until stopped by the shoulder 2^a coming into contact with the nose 4^a; whereupon the operator withdraws his finger from the lever 8 and the dog, under the influence of the spring, engages the rack 9. The jaws 3 and 4 now being 10 apart, the operator places the jaw 4 in engagement with the pipe or nut, and turns the wrench so that the shank 2 will slide in a direction the reverse of that first mentioned, whereupon he again presses downward upon the lever 8, releasing the dog 5 from the rack 9, the shank 2 then slides or drops so as to bring the jaw 3, also, against the pipe or nut. The wrench may also be operated by holding the handle 4^b with one hand and pushing 20 forward and backward the shank 2, by means of the handle 12; the other hand of the operator being used to operate the shank by the handle 12.

For the purpose of a full disclosure of my 25 invention, I have herein described in some detail a specific embodiment thereof; but it will be apparent that numerous changes might be made in the physical embodiment of my invention, within the scope of the appended claims, without departing from the 30 spirit of the invention, and I do not, therefore, desire to be understood as limiting myself, in the broader aspect of my invention, to the specific construction shown and described.

It will be apparent, from the above description, that an important object of my invention is to simplify, improve, and render more efficient that type of wrenches 40 wherein the grip or hold of the jaws is augmented by an appreciable movement of the adjustable jaw toward the fixed jaw, which movement is effected and controlled by the handhold of the operator; and that I provide a quick-acting wrench, having a sure 45 grip, and which releases the grip instantly at the will of the operator.

The grip on the pipe, in my construction of wrench, is, in a measure, like gripping 50 around the pipe. When the grip is taken, the outer end of the jaws come closer together than they do at the pole or shank, and the grip on the object is most secure. This action of the jaws results from the 55 movement toward each other of handles 4^b and 12 under the influence of the operator's grip, at such time shank 4^a having a rocking movement on shank 2, shank 4^a and its jaw being in effect a lever of which the upper or inner end of jaw 4 which bears on the under edge of shank 2 constitutes the fulcrum. This lever object-gripping motion is opposed by spring 6 which holds the handles normally fully separated as in Figs. 60 1 and 3. Thus it will be seen that spring 65

6 performs the double function of holding the parts extended or expanded and at the same time maintains dog 5 in engagement with ratchet 9, thus maintaining the jaws in adjusted relation. The hold of dog 5 is in 70 no way impaired by the rocking motion of shank 4^a above described, the dog and its releasing lever 8 simply turning on their respective pivots and thereby compensating for the rocking motion for impairing the 75 hold of the dog. The proportion, shape, and form of the wrench are such as to withstand all the force required in all its parts. Of course, jaws of other forms than that shown in the drawing may be provided, as 80 are best suited for pipes and other circular or curved objects. Also, the two poles or shanks of the wrenches may be lengthened for special work in inaccessible places.

Having thus fully described my invention, what I claim as new and desire to secure by Letters Patent of the United States is:

1. A wrench comprising a fixed part and a movable part, the fixed part consisting of a shank having a handle at one end and a jaw at its opposite end, the movable part having a shank slidable on the shank of the fixed part, a jaw carried by the shank of the movable part and adapted to coöperate with a fixed-part jaw, a handle projecting from the shank of the movable part and adapted to combine with the fixed-part handle to form a hand grip, and means for holding the fixed and movable parts of the wrench 90 in adjusted relation.

2. A wrench comprising a fixed part and a movable part, the fixed part consisting of a shank having a laterally projecting jaw at one end and a handle at its opposite end, the movable part consisting of a shank adapted to embrace and slide on the shank of the fixed part, a laterally projecting jaw on the movable-part shank adapted to coöperate with the fixed-part jaw, a handle projecting from the movable-part shank at the opposite side of the wrench from the jaws and adapted to coöperate with the fixed-part handle in forming a hand grip, the movable part of the wrench mounted to rock on the fixed part thereof when the respective handles are pressed toward each other and thereby change the relative positions of the jaws, a spring for holding the wrench parts with their handles normally in expanded relation, and releasable means for preventing the movable part from sliding on the fixed part.

3. A wrench comprising a fixed part and a movable part, the fixed part consisting of a shank having a handle at one end and a jaw at its opposite end, and the movable part slidably mounted on the shank of the fixed part and consisting of a shank portion having a handle at one end and a jaw 125

at its opposite end with the jaw adapted to oppose the jaw of the fixed part, the movable part adapted to rock on the fixed part in response to movement of the handles toward each other and with said rocking motion changing the position of the jaws relatively to each other, a spring for opposing said rocking motion, and means for holding the movable part of the wrench from sliding on the fixed part thereof.

4. A wrench comprising a fixed part and a movable part, the fixed part consisting of a shank having a laterally projecting jaw at one end and a handle at its opposite end, the movable part of the wrench consisting of a hollow shank slidably mounted on the fixed-part shank, a laterally projecting jaw on the movable-part shank adapted to co-operate with the fixed-part jaw, a handle projecting from the movable-part shank and adapted to combine with the fixed-part handle in forming a hand grip, the movable part of the wrench adapted to rock on the fixed part thereof upon pressing the handles toward each other and thereby change the relative positions of the jaws, a movable dog for releasably holding the movable part of the wrench from sliding on the fixed part thereof, and a spring adapted to oppose movement of the handles toward each other, the spring operatively connected to the dog for normally maintaining it in holding position.

5. A wrench comprising a fixed part and a movable part, the fixed part consisting of a shank having a jaw projecting laterally from one end thereof and a handle at its opposite end, the movable part of the wrench consisting of a hollow shank slideable on the fixed-part shank, a laterally extending jaw on the movable-part shank adapted to co-operate with the fixed-part jaw, a handle projecting from the movable-part shank and adapted to combine with the fixed-part handle in forming a hand grip, the movable part of the wrench mounted to rock on the fixed-part thereof upon pressing the handles toward each other and thereby change the relative positions of the jaws, a dog movably secured to the movable part of the wrench and adapted to releasably engage the fixed part thereof for preventing relative sliding movement of the wrench parts, a dog-actuating lever pivoted to the movable part of the wrench, and a spring for opposing contraction of the grip-forming handle parts, the spring operatively connected to the dog for opposing movement by the dog-actuating lever.

In testimony whereof, I have hereunto set my hand in presence of two subscribing witnesses.

ROBERT McMILLEN.
